UNITED STATES PATENT OFFICE.

JAMES MARTIN FEERICK, OF NASHVILLE, TENNESSEE.

CASTING APPARATUS.

1,141,738.

Specification of Letters Patent.

Patented June 1, 1915.

Application filed November 24, 1914. Serial No. 873,842.

To all whom it may concern:

Be it known that I, JAMES MARTIN FEERICK, a citizen of the United States, residing at Nashville, in the county of Davidson and State of Tennessee, have invented new and useful Improvements in Casting Apparatus, of which the following is a specification.

This invention relates to improvements in dental casting apparatus, and particularly to machines of this character in which both vacuum and pressure are employed in casting inlays, etc., the object of the invention being to provide a device of this character which is simple of construction, reliable and efficient in operation and which is adapted for receiving mold flasks or cups of different sizes and shapes.

The invention consists of the features of construction, combination and arrangement of parts herein fully described and claimed, reference being had to the accompanying drawings in which:

Figure 1 is a perspective view of a casting apparatus embodying my invention, showing the flask cover retracted. Fig. 2 is a side elevation of the same showing the cover in operative position and the vacuum valve open. Fig. 3 is a vertical longitudinal section through the machine. Fig. 4 is a sectional plan view on the line 4—4 of Fig. 1. Fig. 5 is a detail view of the trip arm and trip finger. Fig. 6 is a section on an enlarged scale through the flask or cup and its holder. Fig. 7 is a detail view of a series of cups or flasks, and all adapted for application to the holder.

In carrying my invention into practice I provide a suitable receptacle 1, serving as a vacuum chamber, and which is supported upon and suitably secured to saddles 2 carried by supporting legs 3. Extending longitudinally through the space beneath the vacuum chamber and between the side sets of legs is a suction pipe 4 supported at one end from the vacuum chamber by a hanger 5 and connected at its opposite end with a vacuum chamber by means of an elbow coupling 6, whereby communication is established between said pipe and chamber. The pipe is adapted for coupling connection at its free end with a vacuum pump or device whereby the chamber 1 may be exhausted of air, and suitably arranged in said pipe is a check valve 7 arranged to open to permit air to exhaust from the chamber 1 and to close to prevent its return. A gage 8 is suit-

ably connected with the chamber whereby the degree of vacuum therein may be determined.

Extending longitudinally above the vacuum chamber is a vacuum pipe 9 connected at one end with the chamber by an elbow coupling 10 and supported at its opposite end by a bracket member 11, which end of the pipe is provided with an elbow coupling 12. Fitted and secured within this coupling 12 is a cup or flask holder 13, which is provided internally with a beveled or chamfered surface 14 and is adapted for the reception of any one of a series of interchangeable cups or flasks, designated generally by 15 in Fig. 7. Each of these cups or flasks has a bottom portion which is adapted to fit snugly within the holder and is formed with a beveled or chamfered surface 16 to snugly engage the surface 14 and thereby form an air tight joint between the cup and flask. It will be evident that the shape of the seat surface 14 of the bearing surface 16 of the cup is such as to permit a fitted flask or cup to shift slightly out of accurate perpendicular position without in any manner breaking a tight joint or seal between the same and the holder. If, therefore, in the operation of the device, the flask cover, herein described, should not come with mathematical accuracy into position, but should move the cup or flask slightly out of accurate position, the joint between the cup and its holder will not be affected and the casting will not be impaired or rendered inoperative. By the use of such a seat and supporting surface forming accurately fitting joint members, I am enabled to employ any number of interchangeable flasks or cups of different shapes and sizes, some of which are shown in Fig. 7, so that various kinds of castings may be made on one and the same machine, it being only necessary to have the joint surfaces of these flasks alike for coöperation with the joint surface of the holder.

A rotary plug valve 17 is arranged in the pipe 9 and provided with a handle or lever 18. This valve controls communication between the flask holder and flask and vacuum chamber and is closed when the lever is disposed in an upright position. It will, of course, be understood that the cup in use is filled with an investment compound, provided with the usual mold cavity, gate and sprue. In the operation of the apparatus,

2
as in other machines of the same type, a vacuum is produced on the sprue side of the valve chamber, whereby the molten metal in the gate is drawn down into the mold chamber communication being established or cut off between the cup and vacuum chamber by opening and closing the valve 17.

It is the purpose of the present invention to provide a means whereby, in addition to the vacuum drawing action above stated, pressure may be generated behind or above the metal in the cup to force the metal down into the mold chamber, which forcing pressure action is established simultaneously with the vacuum drawing action or suction action, so that the molten metal will be caused to fill the mold chamber for the production of a perfect casting. As shown in the present instance, the pipe 9 is composed of two sections united by a four-armed coupling 19, with the horizontal branches of which the said pipe sections are connected. The lower vertical pipe section of this coupling is suitably closed, as by a plug 20, while from the upper vertical branch of the coupling rises a standard 21, which is fitted or otherwise suitably secured therein. To the upper end of this standard is pivoted, as at 22 a hand lever 23 carrying a flask cover 24. This cover is adapted to fit snugly down upon the cup or flask to seal the same during the vacuum drawing process and has an interior packing 25 of and an absorbent material such as "Moldine" or asbestos saturated with moisture, so that when the cover comes into flask closing position the heat of the flask and the molten metal therein will cause evaporation of the moisture in the Moldine or asbestos, whereby steam is produced and caused to exert a working pressure on the molten metal to force the same down into the mold cavity. A trip finger 26 is carried by an arm 27 secured to the lever 23 and is arranged to engage the lever 18 and force the valve open when the lever 23 is moved downwardly to bring the cup 24 into closing position, whereby at the instant of the generation of steam in the top of the mold flask communication will be established between the flask and vacuum chamber for a vacuum or suction action on the base of the flask, by which the metal will be subjected to a double forcing action to insure its passage from the gate to the mold cavity and its perfect conformation to all the variations of surface of the latter. The finger is in the form of a hooked member pivotally connected with the arm 27 and adjustable to

different angles by means of a clamping screw or nut 28, so that it may be disposed to open the valve 17 with accuracy and at the proper time on the downward working movement of the lever 23, the valve 17 being afterward closed by hand as will be readily understood.

It will thus be seen that my invention provides a casting machine which is of maximum simplicity of construction, but at the same time provides for the simultaneous subjection of the metal in the flask to a suction drawing action on one side and steam pressure on the opposite side, whereby it will be drawn into the mold cavity to fill the same and to form a casting conforming in contour to the mold cavity in every respect. It will thus be seen that the construction described permits of the use, in connection with a single holder and vacuum device of a series of molds or flasks of varying shapes and sizes, allowing a wide range of latitude in the casting of inlays and other articles.

I claim:—

In a dental casting apparatus, the combination with a vacuum chamber, and a vacuum pipe communicating therewith, said pipe being arranged in a horizontal position and having means for the attachment of a mold thereto, of a controlling valve in said pipe having a handle vertically disposed when the valve is in closed position, an upright rising from the pipe, a hand lever pivotally connected with said upright and carrying a cap having a lining of absorbent material, adapted upon the downward movement of the lever to move into mold closing position, a valve actuating arm projecting at right angles from the lever, a sleeve carried by said arm and adjustable longitudinally of the lever, said sleeve being provided with a set screw for securing it in adjusted position, a finger having a hook-shape end to engage and move the valve handle from a normally vertical to a horizontal position, whereby the valve is open to establish communication between the vacuum chamber and mold, said finger being pivotally mounted for adjustment upon said arm, and means for securing said finger in adjusted position.

In testimony whereof I affix my signature in presence of two witnesses.

JAMES MARTIN FEERICK.
